UNITED STATES PATENT OFFICE.

JOHN McGAFF, OF TOLEDO, OHIO.

ROTARY HEATING-FURNACE.

No. 827,813.

Specification of Letters Patent.

Patented Aug. 7, 1906.

Application filed April 13, 1906. Serial No. 311,498.

To all whom it may concern:

Be it known that I, JOHN McGAFF, a citizen of the United States, and a resident of Toledo, in the county of Lucas and State of Ohio, have invented certain new and useful improvements in Rotary Heating-Furnaces; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to furnaces for the working of all kinds of iron or steel scraps, and particularly to "flame-furnaces" or the kind in which the work is not "embedded" or mixed with the fuel, but is subjected to the 20 flame and heat arising therefrom.

The object of my invention is to simplify and cheapen the initial heating and working of such metals into balls by the provision, in combination with the combustion-chamber, 25 of a rotary heating-chamber which is so shaped as to cause the metal therein to be continuously puddled or worked into a ball during the heating thereof and the slag and cinders segregated therefrom, thus obviating 30 the skilled labor heretofore necessary to puddle or work the metal into balls.

The construction, operation, and arrangement of the parts of my invention are fully described in the following specification, and 35 illustrated in the accompanying drawings, in which—

Figure 1 is a plan view, and Fig. 2 a central longitudinal vertical section, of the furnace embodying my invention.

40 Referring to the drawings, 1 represents the fuel or combustion chamber, 2 the rotary heating drum or chamber, and 3 the smoke-stack or chimney of the furnace. The fuel-chamber 1 is provided in its side with the 45 usual stoke-hole 4 and has its roof preferably arched and inclined inwardly toward the heating-chamber 2 and its inner side formed with the usual bridge 5, over which the flames and highly-heated gases from the burning 50 fuel are required to pass to enter the heating-chamber.

The heating drum or chamber 2 is of cylindrical form and has its ends contracted, as shown, to form the restricted entrance and 55 exit passages 6 and 7, respectively, and the intermediate annularly-bulged portion 8,

which forms a trough in which the metal is worked. The exit end 7 of this drum communicates with the chimney-flue through a suitable opening 9 therein, while the entrance 60 end thereof is flared or tapered outwardly to form a conical mouth which abuts against the inner end of the fuel-chamber with its inner upper edge coinciding with the corresponding edge of said fuel-chamber and has 65 the radius of its rim substantially that of the arc described by the arch of the fuel-chamber roof at such point. The drum 2 is shown as being formed of an outer casing of sheet metal having an inner lining of fire-brick, 70 fire-clay, or the like. A door or doors 10 are positioned at one side of the bulged portion of this drum to close an opening therein through which the metal is inserted or withdrawn. A plurality of openings 11 are provided through the casing of the bulged portion of the drum 2 for the drainage of slag and cinders therefrom. These also form windows through which the metal within the 75 chamber may be inspected.

80 The drum is supported at its ends in proper position between the fuel-chamber 1 and stack 3 by the supports 12 12, carrying the grooved segmental stirrups or members 13 13, in which the annular ledges or shoulders 14 85 14 at the ends of the heating-chamber rotatably rest, as shown.

A sprocket-wheel 15 is mounted on the reduced end 7 of the drum 2 and meshes with a drive-chain 16, by means of which a rotary 90 movement is communicated to said drum, or it may be driven in any other suitable manner.

The operation of my invention is as follows: The scrap metal being deposited in the 95 drum 2 through the door-opening therein, the door 10 is then closed and the rotation of the drum started. The flames and heated gases arising from the fuel in the combustion-chamber 1 pass over the bridge 5 therein, and impinge against the upper inwardly and downwardly inclined surface of the conical mouth 6 of the heating drum or chamber 2 and are caused thereby to take a downward course and be concentrated upon the work in the 100 lower portion of the trough 8. The rotary movement of the drum causes the metal to be kept continually turning over, so that all sides thereof are acted upon by the heat, and as the mass of metal approaches a welding 105 heat causes it to be rolled into a ball, as shown at 17, thus effecting a quicker and 110

- more even heating of the mass of metal than would otherwise be the case and causing it, due to its weight, to be compressed into a more solid mass than is possible by hand.
- 5 The cinders and slag which become separated from the rolling mass during the heating process drop through the openings 11 in the drum to the floor. In the working of some classes of metal—such, for instance, as pig-iron—it
- 10 is preferable to plug the openings 11 and to draw the cinders and slag from the drum at proper intervals. When the mass has been heated and rolled to the desired state, the rotation of the drum is stopped, the door opened
- 15 at the under side thereof, and the ball allowed to drop out.

I wish it understood that I do not desire to be limited to the exact details of construction shown and described, for obvious modifications will occur to a person skilled in the art.

Having thus described my invention, what I claim as new, and desire to secure by Letters Patent, is—

- 25 1. In a furnace, a fuel-chamber, a rotatable cylindrical drum having one end opening contracted with its mouth of conical form and in communication with the exit from the fuel-chamber, whereby the flames are reflected downwardly in the drum, and having its other end contracted and communicating with a stack.
- 30 2. In a furnace the combination with the fuel-chamber having its flame-exit near its

top and formed with an arched roof, of a rotary heating-chamber having its ends contracted to form an intermediate trough portion and its entrance end flared and abutting the side of the fuel-chamber in communication with its exit and having its inner surface coinciding with the inner surface of the roof and substantially describing a circle of which the roof is an arc.

3. A furnace having in combination a fuel-chamber and a horizontally-disposed rotary drum communicating at one end with the exit of the fuel-chamber and at its other end with a chimney, said drum being annularly bulged intermediate its ends to form an internal trough and having such bulged portion provided with a door and drainage openings, substantially as described.

4. The combination with the fuel-chamber, of a horizontally-disposed rotary cylindrical heating-chamber having an axial opening therethrough, its entrance formed with a flared mouth whereby the flames striking the upper surface thereof are deflected downwardly, and its intermediate portion diametrically expanded to form a trough having drainage-openings through its walls.

In testimony whereof I have hereunto signed my name to this specification in the presence of two subscribing witnesses.

JOHN McGAFF.
